J. M. WALTON.

SPARK PLUG.

APPLICATION FILED JULY 15, 1915.

1,185,742.

Patented June 6, 1916

FIG. 1.

UNITED STATES PATENT OFFICE.

JOHN M. WALTON, OF NEW ORLEANS, LOUISIANA.

SPARK-PLUG.

1,185,742.

Specification of Letters Patent.

Patented June 6, 1916.

Application filed July 15, 1915. Serial No. 40,063.

To all whom it may concern:

Be it known that I, JOHN M. WALTON, a citizen of the United States, residing at New Orleans, in the parish of Orleans and 5 State of Louisiana, have invented certain new and useful Improvements in Spark-Plugs, of which the following is a specification, reference being had therein to the accompanying drawing.

10 My present invention relates to improvements in spark plugs and more particularly to that type shown in my Letters Patent No. 1,132,811, dated March 23, 1915, one object of the present invention being the 15 provision of means whereby that portion of the insulator inclosed within the metal casing may be readily cleaned without dismantling the parts, such casing coöperating with a supporting bushing which after once assembling within the engine does not have to be removed.

A further object of the present invention is the provision of a cutting edge upon the insulator carrying casing whereby any collection of carbon within the supporting bushing will be automatically removed as the insulator carrying casing is moved into and out of position.

With the foregoing and other objects in view which will appear as the description proceeds, the invention resides in the combination and arrangement of parts and in the details of construction hereinafter described and claimed, it being understood that 35 changes in the precise embodiment of the invention herein disclosed can be made within the scope of what is claimed without departing from the spirit of the invention.

In the accompanying drawings: Figure 40 1 is a side elevation of a spark plug constructed according to and embodying the present invention. Fig. 2 is a vertical central sectional view therethrough. Fig. 3 is a detail side elevation of the insulator carrying casing *per se*. Fig. 4 is a bottom plan view of the spark point forming disk. Fig. 45 5 is a detail view partly in section of the gasket used between the engine and the supporting bushing.

50 In the accompanying drawings, the numeral 1 designates the supporting bushing provided with the exterior screw threads 2 and with the double diameterd portions 3 and 4 providing the gasket receiving shoulder 5, for the reception of the metal ring gasket 6.

The insulator carrying casing 7 is provided with the frusto conical sparking end 8 having the concentric channel 9 in communication with the chamber 10. An opening 11 is formed in the wall of the casing 7 and thus permits access to the chamber 10 and also to the lower end of the insulator 17, thus permitting these parts to be thoroughly cleansed without dismantling the insulator. 65 The shoulder 12 of the casing 7 is adapted to rest upon the gasket 6 with the threaded portion 13 engaging the threaded portion 14 of the bushing 1, the portion 14 of the casing providing a wrench engaging end 70 therefor.

The upper end of the chamber 10 is counterbored to provide the shoulder 15 for the reception of the annular shoulder 16 of the insulator 17, the shoulder 18 of the insulator being held seated and properly locked in place by means of the locking bushing 19.

The insulator is provided with the bore 23 terminating in the chamber 20 for the reception of the fixed disk 21 carried by the stem 22, said stem 22 extending through the bore 23, and being provided with the reduced end 24 which extends through the casing 10 and opening 9 thereof to a point below the sparking terminal 30. The sparking disk 25 is riveted at 26 upon the lower end of the reduced stem 24, and as shown in Fig. 4 is provided with the curved cuts 27 which provide when the respective sections have the points 29 bent toward the 90 fixed sparking terminal 30, the spaces 28, which permit any lubricant carried in the charge to be drained therefrom.

The edge 31 of the casing 7 coöperates with the wall of the bore of the bushing 1 as 95 the casing is inserted and withdrawn to remove any collection of carbon, the exterior of the reduced end of the casing 7 fitting snugly within the bushing 1. Provided upon the lower end of the casing 7 are a plurality of spiral grooves 32 to drain any oil that may enter in the space between the bushing 1 and casing 7, and especially when the present plug is used in a horizontal position.

The stem 23 is properly held in place by 100 means of the metal cap 33, the resilient washer 34 and the nut 35, a terminal attaching nut 36 being also provided.

The gasket 37 is preferably made from sheet copper or other similar malleable 110 metal and incases a filling 38 of heat resisting material such as asbestos.

From the foregoing description taken in connection with the drawing it is evident that this construction provides a means whereby a casing 7 carrying an insulator and sparking portions may be readily removed from the supporting bushing for cleaning, and that by reason of the fact that the chamber thereof is accessible through the side the collection of carbon upon the lower 5 end of the insulator and the electrode carried thereby may be thoroughly cleansed without disturbing the relative adjustment of the parts. It is also apparent that by cutting the disk 25 as illustrated with a 10 plurality of spiral radial incisions that a plurality of sharper points 29 are provided than in my former patent, and that therefore better sparking facilities are secured. It is also apparent that greater strength at 15 the supporting portion of the separated pieces of the disk is had as the base thereof adjacent the rivet 26 is widened.

What I claim as new is:—

1. A spark plug including a supporting 25 bushing, a casing insertible therein and provided with a chamber with an opening through the wall thereof, said opening being normally closed by the supporting bushing, a fixed electrode carried upon the lower 30 end of the casing for projection exteriorly of the bushing, an insulator carried within the casing and having the end therewithin exposed through the opening, and an adjustable electrode extending through the insulator and the chamber of the casing to a 35 point exteriorly of the fixed electrode.

2. A spark plug including a supporting bushing provided with a smooth cylindrical bore, and an insulator and sparking terminals carrying casing insertible within said bore and provided with a bore cleaning por-

tion, the exterior of the casing being provided with a plurality of oil draining grooves opening at one end of the bushing.

3. A sparking plug including a supporting bushing having an internal double diametered portion providing a gasket receiving shoulder, a casing provided with a chamber having a reduced opening through one end, the exterior of the casing adjacent said end being provided with a cutting edge terminating in a frusto conical electrode, an insulator mounted in the casing, a stem carried by the insulator and projecting through the reduced opening below the electrode, and a disk electrode provided with a plurality of spirally cut radial incisions forming a plurality of sparking terminals and oil outlets.

4. A sparking plug including a supporting bushing having an internal double diametered portion providing a gasket receiving shoulder, a casing provided with a chamber having a reduced opening through one end, the exterior of the casing adjacent said end being provided with a cutting edge 65 terminating in a frusto conical electrode, an insulator mounted in the casing, a stem carried by the insulator and projecting through the reduced opening below the electrode, and a disk electrode provided with a plurality of 70 spirally cut radial incisions forming a plurality of sparking terminals and oil outlets, said casing being provided with a relatively large opening through the wall thereof to expose the interior thereof and the insulator for cleaning.

In testimony whereof I affix my signature.

JOHN M. WALTON.
